(57) **CLAIM**

The ornamental design for a telephone, as shown and described.

DESCRIPTION

FIG. 1 is a front, right side, bottom perspective view of a telephone showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reference front elevational view thereof showing a state in which a receiver is taken from its rest of a telephone main body.

The broken lines in FIGS. 3, 7 and 8 depict parts of the telephone that form no part of the claimed design.

1 Claim, 7 Drawing Sheets
